SHOTGUN BARREL AND CHOKE

George G. Oberfell, Bartlesville, Okla.

Application February 27, 1950, Serial No. 146,558

9 Claims. (Cl. 42—79)

1

This invention relates to improvements in shotgun barrels. In one specific aspect it relates to shotgun barrels having chokes. In another specific aspect it relates to improved choke sections for shotgun barrels.

In the prior art of shotguns, sometimes called scatter guns, it was found that with a true cylindrical bore that the shot pellets become unduly scattered at an arbitrary distance of 40 yards. In order to reduce this scattering the inventors in the prior art have attached to, or built into the shotgun barrel, a choke section having a tapered bore of decreasing diameter toward the muzzle. These shotgun bores having choke sections of the prior art reduce the scattering of the shot at 40 yards, but do so by unduly concentrating the shot pellets in the center of the pattern. The pattern of the perforations on a target at 40 yards produced by the shot pellets of a shotgun charge fired through a shotgun barrel containing a conventional choke shows many void spaces, known as patches, of an arbitrary diameter of 5" inside of a 30" circle, which last circle is drawn so as to include the maximum number of perforations. Each of these patches represents a place where a duck, or other game animal, could be located within 15" of the center of the shot pattern and still escape without critical injury. This is due to an uneven distribution of the pellets over the 30" diameter pattern with an undue concentration of pellets in or near the central portion and many void patches or almost void areas in various portions of the 30" pattern, especially in the outer portions thereof. This results in a game animal in one portion of the pattern where there is a clustering of pellets being filled with an excessive number of shot, which reduces its value for food, whereas another game animal located at a different point in the pattern may escape unwounded, or may not be critically wounded and may escape in a crippled condition.

Attempts have been made in the prior art to counteract this tendency of the choke to concentrate the shot in the center of the pattern by rifling the choke section with helical grooves, but such rifling has proved ineffective because it sets the shot charge as a body in rotation about the longitudinal axis of the shotgun barrel, and when the shot charge emerges from the muzzle of the shotgun the individual pellets thereof spread rapidly in all directions due to centrifugal force.

In the prior art, as the choke was increased by decreasing the smallest diameter of the bore of the choke section, the percentage of pellets in the target increased up to a maximum after which further increase in the choke resulted in a scattering instead of a further concentration of pellets.

I have found that by providing a shotgun choke

2

having a bore generally tapering toward the muzzle and of reduced diameter from the bore of the shotgun barrel with a plurality of transverse grooves in its wall of said reduced diameter, the pellets in the shot charge passing through this bore, which contains depressions and elevations provided by said transverse grooves, are so agitated that they are evenly distributed in a pattern, arbitrarily of 30" diameter, at a suitable range, arbitrarily taken as 40 yards. Also the pattern efficiency, i. e., percentage of the pellets in the shot charge placed in the 30" diameter target, is increased over that obtained with the same diameter chokes of the prior art.

One object is to provide an improved choke for shotguns.

Another object is to increase the uniformity of distribution of shot pellets in flight, as evidenced by patterns made in paper targets of arbitrary diameter at arbitrary ranges.

Another object is to reduce the number of game animals which escape being killed, which are crippled and escape, or which are filled with excessive numbers of shot pellets.

Another object is to provide improved shotgun chokes made by simple and inexpensive mass production methods.

Another object is to provide shotgun chokes of simple but improved design which are inexpensive, easy to produce, rugged, and which will concentrate the shot pellets in the shot pattern with uniform distribution of the shot over a limited diameter of pattern, but without local concentration of shot in the pattern with resulting void portions, or patches, of any substantial diameter.

Another object is to increase the pattern efficiency, i. e., the number or percentage of pellets of the shot charge placed in the target by the gun.

Numerous other objects and advantages will be apparent to those skilled in the art upon reading the accompanying specification, claims and drawings, in which:

Figure 1 is an elevational cross-sectional view of a shotgun embodying the invention, with parts broken away.

Figure 2 is an elevational cross-sectional view of a portion of the muzzle of a shotgun showing one modified form of choke embodying my invention.

Figure 3 is a cross-sectional view of the structure shown in Figure 2 taken along the line 3—3 looking in the direction indicated.

Figure 4 is a quarter-sawed elevational view of another modification of a shotgun choke embodying another modification of the invention.

Figure 5 is an elevational view of the pattern made on a target by pellets from a shotgun having one type of conventional choke of the prior

art, with circles drawn to aid in the study of the distribution of the pellets.

Figure 6 is a view similar to Figure 5 but taken of a representative pattern resulting when a shotgun choke embodying the present invention is used.

In Figure 1 a conventional shotgun generally designated as 7 is provided with a choke section generally designated as 8, which choke section embodies the present invention. This choke section may be an integral part of the barrel 9 of the shotgun as shown in Figure 1, or may be a separable extension generally designated as 11 in Figure 2.

Shotgun 7 as shown in Figure 1 is entirely conventional except as to choke 8. It consists of a barrel 9 having one end sealed by breach block 12 which contains a firing mechanism (not shown) which may comprise a hammer 13. A conventional shotgun shell 14 comprises a base 16, having a percussion cap or primer 17, powder charge 18, powder chamber 19, wads 20, 21 and 22, shot charge 23 front wad 24, and container 26. Container 26 is either crimped at 27 to retain front wad 24, or 27 is folded in some manner (not shown) in front of shot 23, in which case front wad 24 may be eliminated.

Shotgun barrel 9 has a bore comprising a chamber 26, a connecting conical portion 29, a substantially cylindrical bore 31, and a choke section 8. As all parts are conventional and well known to those skilled in the art, except the muzzle choke section 8, further description of the other parts of the shotgun is unnecessary.

In Figure 1, choke section 8 is formed integral with barrel 9 in the following manner:

Barrel 9 is preferably provided with a frustum-shaped conical bore 32 of decreasing diameter toward the muzzle. While bore 32 may have a convexly and/or concavely bellied taper (not shown) and still embody this invention, a plain conical taper is preferred. The taper of bore 32 may vary considerably, and I have found that the conventional amount of taper in shotgun chokes is satisfactory with the present invention, that shown in Figure 1 being representative. However, Figure 1 should be regarded as illustrative and not as limiting as to degree of taper, or shape. For example, many conventional chokes of the prior art have a cylindrical bore known as "the parallel" (not shown) of the same diameter as the muzzle end of conical bore 32 and following the same. Grooves similar to 33, 34, 36 and 37 may be cut solely in said parallel, although it is preferred to cut at least some or all of these grooves in the conical portion where they are more exposed for contact with the pellets of shot.

In the wall 32 of barrel 9 there is cut, preferably by a tool in a lathe or boring machine (not shown), a plurality of transverse annular circumferential grooves 33, 34, 36 and 37, leaving intermediate land surfaces 38, 39 and the like. The grooves and lands constitute alternate adjacent depressions and elevations in the bore of the gun barrel in Figure 1, or in the bore of the choke tube in Figure 2. A plane passing through the gun barrel and lying parallel to the edges of the lands and the grooves would also be at right angles to the longitudinal axis of the gun barrel. The edge or boundary between the grooves and lands may be sharp or rounded. Thus, in addition to providing enlarged bores at 33, 34 and 36 for the pellets 23 to expand into, there are also provided transverse shoulders 41 with either

sharp or rounded edges which agitate the pellets 23 and force the same back into bore 32 in the land portions 38 and 39 thereof. The number of such grooves, the width, depth and distance between the grooves may vary considerably with somewhat similar results. However, I prefer to use a groove width for grooves 33 of from one-half to ten times the diameter of pellets 23, and while lands 38 can vary from the grooves in width, I prefer to have them substantially the same width as grooves 33. While the number of grooves 33 can vary, I prefer from 2 or even preferably 3 to 20 grooves, a plurality giving distinctively superior results to a single groove, particularly when the length of the grooved section of the barrel is from one to three times the length of the body of the shot charge of the shotgun cartridge. The grooves 33 preferably are from .02" to .001" in depth. Very successful results were obtained with 6 grooves such as 33, each groove being .003" deep and $\frac{1}{8}$ " wide separated by lands such as 38 each $\frac{1}{8}$ " wide. As the grooves are made shallower than .001" there is less beneficial effect, but they can be deeper than .02", but such additional depth does not provide essentially better disposition of the shot.

In Figure 2 the choke 11 is provided as a separable tube 42 which is secured to the end of shotgun barrel 43 by any suitable connecting means such as the threaded coupling 44, or by a bayonet-joint type of connection (not shown). Obviously, choke 8 of Figure 1 could have been made separable and so secured to barrel 9.

In Figure 2 choke 11 is provided with a frustum-shaped conical bore 46 of decreasing diameter toward the muzzle 47. The taper is more pronounced than in Figure 1, but any taper used in prior art shotgun chokes is satisfactory. Tube 42 may be provided with wrench holes 48 to aid in attaching the same, and when present such holes act partly as a muzzle brake in reducing the recoil of the shotgun and act to relieve some of the pressure. However, holes 48 are not essential and may be eliminated.

Semi-annular circumferentially disposed transverse grooves 49, 50 and 51 are provided, preferably with a plurality of such grooves in each transverse plane (such as plane 3-3) with the grooves in alternate planes being staggered to place grooves 49, 50 and 51 (for example) overlapping in echelon around the entire circumference of the choke 11.

While the exact shape of grooves 49, 50 and 51 is not critical as long as substantially transverse shoulders 52 of sharp or rounded edges are provided and there are no helical elements tending to cause rotation of the shot charge which would scatter the same, economy dictates that grooves 49, 50 and 51 be made in a simple manner.

As shown in Figure 3, possibly the simplest manner of making the semi-annular grooves such as 49, 50 and 51 is by grinding or cutting the same in the wall 46 with a rotating circular cutter (not shown) of less diameter than corresponding portion of bore 46. This cutter (not shown) can be inserted longitudinally in bore 46 and then moved laterally back and forth in each transverse plane (such as 3-3) to cut the semi-annular grooves such as 49 and 50, and then removed.

Figure 4 shows a choke generally designated as 53 which is made in an inexpensive manner by stamping, but which may embody annular grooves such as 59 similar in effect to the groove 33 of Figure 1 and/or semi-annular grooves such as

54, 56 and 57 similar in effect to grooves 49 and 50 of Figure 2. For the purpose of illustration the semi-annular grooves are shown as depressions 54, 56 and 57 stamped in the wall 53 of choke 53, while an annular groove 59 has been rolled or spun in the wall 53.

As depressions 54, 56, 57 and 59 in Figure 4 are formed in choke 53 by deforming the metal, there will be bosses 61 or ridges 62 on the exterior of choke 53 which have an attractive design appearance of advertising value. Holes 63 are the same as in Figure 2, and threads 63 are similar to those engaging coupling 44 in Figure 2.

It will be clearly seen by viewing the tapered portion 8 in Figure 1 that the angle of the shoulder 41 formed between the wall forming the outlet end side of each groove 33, 34, 36 and the respective adjacent land 38, 39 in the direction of the outlet end of choke 8 is an obtuse angle. The corresponding shoulder 52 in Figure 2 is also obtuse. The corresponding shoulder 59 in Figure 4 is even more obtuse because of the beveled slope caused by stamping, rolling, or spinning the metal as visible in the drawings and explained in the second paragraph preceding. This obtuse angle approaches a right angle as a lower limit and does not include acute angles, as obviously acute angles will cut into the passing shot pellets.

In any of Figures 1 to 4 it is entirely satisfactory to mix both annular and semi-annular grooves, or use them separately, with or without overlapping, but best over-all results as to economics of manufacture, attractive appearance of the article in commerce, and similar factors, make it preferable to have all the groove elements similar, and theoretically there should be complete overlapping of grooves around the entire circumference in order that the shot charge will be uniformly treated in passing through the bore of the choke, which uniform treatment should aid in attaining uniform distributions of the shot in the pattern.

Although in Figures 1 to 4 it is not necessary to have exactly transverse circumferential grooves, nor need the entire extent of any groove be transverse, the type of depressions or elevations provided in the bore of the gun should be such as to avoid imparting a rotating motion of the body of the shot charge around the longitudinal axis of the gun bore, as is imparted to a rifle bullet as it passes through the helical grooves of a rifle. If a helical or slanting portion (not shown) of one groove should impart such rotation to a pellet it is preferred that the pellet be subjected before leaving the muzzle to a like impulse in the opposite direction by an oppositely disposed helical or slanting portion. Obviously it is preferable not to have any such helical or slanting grooves, or portions of grooves, but they may be employed provided they are so disposed that their net effect is that of transverse circumferential grooves.

Figure 5 shows a pattern shot into a paper target at 40 yards using a conventional choke of the prior art. This pattern is worse than would be expected from a pattern of 127 pellets according to Table 1 and, therefore, is not representative of the prior art, but is chosen because it illustrates the uneven distribution of shot very clearly. Patterns which are representative of the prior art are discussed below and are tabulated in Tables 1 and 2. They also had uneven distribution of the type shown in Figure 5, although it was not so evident. In Figure 5, a 30"

diameter circle 64 is drawn to include the maximum number of pellet holes 66. A concentric inner circle 67 of 20" diameter aids in evaluating the results. Because of the undue concentration of shot by the conventional choke in the central portion of the pattern around such points as 68, there are void areas surrounding widely spaced single shot such as 66, and there are large numbers of completely void areas (known as patches) of an arbitrary diameter of 5", as indicated by 5" diameter circles 69.

Figure 6 shows the improved results of the present invention on a target of the same diameter at the same range and under conditions similar to those involved in Figure 5. When circles 64 and 67 are drawn, it is seen that the pellets 66 are quite evenly distributed, that there is no undue concentration of pellets such as at 68 of Figure 5, and that there are not patches 69. Figure 6 is regarded as representative of the results to be expected with the present invention.

EXAMPLE

I have analyzed many shotgun patterns for the purpose of determining the patchiness of such patterns. Using as a measure of patchiness the number of pellet-hole-free circular areas with a diameter of five inches within the pattern, I have found that the average patchiness of shotgun patterns using the conventional shotguns, shotgun chokes, shotgun shells, and shotgun pellets of the prior art which are obtainable on the open market, will be substantially as shown in the example, Table 1, which follows.

TABLE 1
Relation between the number of pellets and the number of separate 5-inch diameter circular patches in 30-inch patterns produced by guns and chokes of the prior art

	No. of pellets	No. of patches	No. of pellets	No. of patches	No. of pellets	No. of patches
45	125	22	125	7	225	2
	50	17	150	5	250	1
	75	12	175	4	275	1
	100	9	200	3	300	0

The relation between the number of pellets and the number of patches in 30" shotgun patterns as shown in the table immediately above represents the average results of numerous tests involving a large number of variables such as: different guns, different gauges of guns, different sizes of shot, shotgun shells of different ammunition manufacturers, different powder charges, different chokes, choke devices of different manufacturers, as well as different weather and climatic conditions. Although the table serves as a good guide for patchiness expectations, control tests should be run for the purpose of direct comparison when evaluating the effect of any one variable upon patchiness of patterns.

There are two undesirable effects which are involved in the imperfect patterns of the prior art as clearly shown in Figure 5. First, there is a tendency of the choke to concentrate the shot in the 20" circle 67. Of the 127 pellets inside the 30" circle 64 there are 78 pellets inside the 20" circle, and only 49 pellets between the 20" and 30" circles. In Figure 6 where the present invention is used there are 178 pellets inside the 30" circle of which 88 pellets are inside the 20" circle and 90 pellets are between the circles, a substantially even distribution. The

second bad effect in Figure 5 is that the pellets in passing through the barrel of the shotgun and chokes of the prior art tend to weld or stick together, and while broken apart again by air resistance, little closely spaced groups of the pellets still tend to appear in the pattern, with the resulting void areas, or patches 69, being increased in number. As shown in Figure 6, my invention tends to eliminate both of these undesirable effects and distributes the shot quite evenly (for shot pellets) over the entire surface inside the 30" diameter ring 64 as well as inside the 20" diameter ring 61.

I have experimented with several mechanical means having for their objective preventing or reducing the tendency of the charge of pellets to ball or weld together as it passes through the various portions of the gun, including the choke. If the bore of the shotgun contains grooves as does a rifle, the charge of pellets, after it passes through the bore of the gun, will undergo excessive scattering of pellets before they reach the target. This scattering effect can be lessened by making fewer, smaller and more shallow grooves and having them of very low pitch, say, not more than one complete turn for 20" barrel length, but I have found that any helical grooves or elements in the barrel create more scattering of the pellets in the pattern than desirable. I have found that if the grooves are circular or annular in shape, being placed circumferentially in the bore of the barrel or in the bore of the choke tube, I obtain a very much better and less patchy pattern than I have been able to obtain in any other manner. I have analyzed several hundred patterns, and the patterns with the most even distribution of pellets were obtained with a choke device containing such circumferential grooves as shown in Figure 1.

The two patterns compared below in Table No. 2 are representative and were made with the same 12-gauge gun firing shells from the same box purchased on the open market. These shells contained 3 1/4 drams of powder and 1 1/4 ounces of No. 6 shot (about 275 shot each, more or less). A 30" pattern was made on targets 40 yards distant from the muzzle of the gun. In test No. 1 below, a conventional choke was used, and was representative in producing a pattern with 4 patches. Figure 5 does not show the target of test No. 1, but shows instead a considerably worse pattern with 10 patches 69, being only used for illustrative purposes. Figure 6, however, is an accurate scale reproduction of the representative pattern obtained in representative test No. 2 when employing the present invention.

TABLE 2

Numerical analysis of patterns of shot pellets fired from shotgun with choke tubes

	Test No. 1 with new full choke tube with a smooth bore	Test No. 2 with new full choke tube with circumfer- ential grooves
Number of pellets in 30" pattern	164	178
Pattern efficiency	60	65
Increase in pattern efficiency: Percent of control	Control	8.5
Number of 5" diameter patches	4	0
Decrease in patchiness: Percent of control	Control	100
Number of 5" diameter patches which would be predicted by Table 1	4	4
Decrease in patchiness: Percent of those predicted by Table 1	0	100

Explanation.—The new choke tube for test No. 1 was purchased in the open market from a manufacturer of choke devices. Test No. 2 was conducted with a duplicate new choke tube from the same manufacturer, except that the choke tube for test No. 2 had been provided with 6 circumferential grooves 1/8" wide and .003" deep spaced 1/8" apart in the manner shown in Figure 1, although the choke tube was detachable as shown in Figure 2 at 44.

The ordinary shotgun cartridges or shotgun shells which are obtainable through the regular channels of trade, when used with my invention, will produce better, more even and more regular patterns, with less 5" diameter patches, or less void spaces of any considerable area.

While I have described and shown above certain modifications embodying my invention and for purposes of illustration and have given the result of representative tests in order to explain the invention, such disclosures should not be regarded as limiting the scope of the invention which is defined by the following claims.

I claim as my invention:

1. A shotgun choke comprising in combination a tube having a bore, said bore having an inlet end and an outlet end for shot pellets, a portion of said bore being tapered with a decreasing diameter in the direction of said outlet end to choke said shot, said tube being adapted to be disposed with its inlet end aligned with and communicating with the muzzle of a shotgun barrel to form a continuation thereof of initially the same internal diameter, the walls of said tube forming the decreased diameter tapered portion of said bore being formed with alternate transverse lands and transverse grooves in which the angle of the shoulder formed between the wall forming the outlet end side of each groove and the adjacent land in the direction of said outlet end is an obtuse angle whereby shot pellets fired through said bore of said choke are agitated without undue deformation by alternate expansion of some of said pellets into said grooves and contact with said shoulders.

2. The combination of a shotgun having a barrel and a shotgun choke forming a continuation of the muzzle end of said barrel of initially the same internal diameter, said shotgun choke comprising in combination a tube having a bore, said bore having an inlet end and an outlet end for shot pellets coming from said shotgun barrel, a portion of said bore being tapered with a decreasing diameter in the direction of said outlet end to choke said shot, said walls of said tube forming the decreased diameter tapered portion of said bore being formed with alternate transverse lands and transverse grooves in which the angle of the shoulders formed between the wall forming the outlet end side of each groove and the adjacent land in the direction of said outlet end is an obtuse angle whereby shot pellets fired through said bore of said choke are agitated without undue deformation by alternate expansion of some of said pellets into said grooves and contact with said shoulders.

3. The combination of claim 1 in which the grooves are from .02 to .001 inch deep.

4. The combination of claim 1 in which the grooves are annular.

5. The combination of claim 1 in which the grooves are recessed into the wall of the choke and the exterior of the choke is cylindrical.

6. The combination of claim 1 in which the

walls of the choke are displaced outwardly at the grooves.

7. The combination of claim 1 in which the transverse grooves are semi-annular with a plurality in one transverse plane.

8. The combination of claim 1 in which the grooves lie in a plurality of transverse planes with the grooves in one transverse plane overlapping in echelon the grooves in a second transverse plane.

9. The combination of claim 1 in which the grooves are recessed into the wall of the choke

and the exterior of the choke is cylindrical and said grooves are semi-annular.
